H. P. COUNCILMAN

IMPACT FIRING MECHANISM

Filed June 22 1922

UNITED STATES PATENT OFFICE.

HALSTEAD P. COUNCILMAN, OF ASHEVILLE, NORTH CAROLINA, ASSIGNOR TO SECRETARY OF WAR OF THE UNITED STATES OF AMERICA, TRUSTEE.

IMPACT FIRING MECHANISM.

Application filed June 22, 1922. Serial No. 570,250.

(FILED UNDER THE ACT OF MARCH 3, 1883, 22 STAT. L., 625.)

To all whom it may concern:

Be it known that I, HALSTEAD P. COUNCILMAN, a citizen of the United States, and a resident of Asheville, county of Buncombe, 5 and State of North Carolina, have invented an Improvement in Impact Firing Mechanism, of which the following is a specification.

The invention described herein may be 10 used by the Government, or any of its officers or employees in prosecution of work for the Government, or by any other person in the United States, without payment to me of any royalty thereon.

15 The subject of this invention is an impact firing mechanism intended, primarily, for use in impact grenades, though not confined to such use.

In designing the firing mechanism for an 20 impact grenade so as to gain the highest efficiency it is necessary to provide means for functioning the primer in whatever position the grenade may engage its objective and which may be held absolutely safe 25 during handling and transportation.

The object of the present invention is, 30 therefore, the provision of a firing mechanism to function the primer upon impact in any direction and of means for retaining the firing mechanism unarmed and safe.

I carry out these objects by providing 35 an unbalanced weighted striker with means for holding the striker against movement and for isolating the primer from the detonator fuse or explosive charge as the case may be.

With these and other objects in view 40 which will hereinafter more fully appear the invention resides in the novel arrangement and combination of parts and in the details of construction hereinafter described and claimed, it being understood that changes in the precise embodiment of the invention herein disclosed may be made 45 within the scope of what is claimed without departing from the spirit of the invention.

One practical embodiment of the invention is illustrated in the accompanying drawing, wherein:

50 Fig. 1 is a longitudinal sectional view of

a grenade constructed in accordance with the invention;

Fig. 2 is a similar view showing the parts in armed position;

Fig. 3 is an enlarged fragmentary sectional view showing the striker in firing position.

Referring to the drawing by numerals of reference:

1. Indicates an ordinary type of grenade 60 body adapted to receive an explosive charge and having a detonator tube or casing 2 suitably secured therein and extending axially thereof.

One end of the grenade body is recessed, as 65 at 3, to provide a cavity for the reception of the firing mechanism.

Within the cavity 3 is placed a primer carrier or casing 4 which is preferably of cylindrical formation and provided with a 70 bore 5 extending axially thereof and preferably concentric with the tube 2 when assembled. The bore 5 is countersunk at one end to provide a seat for the primer 6. A bore 7 extends diametrically of the carrier 4 75 and communicates with the bore 5 and is of slightly greater diameter than the bore 5. As will be understood, the bore 5 furnishes a vent for the flash of the primer to permit ignition of the detonating charge 80 which vent is normally completely closed by a safety pin to be hereinafter described, which is positioned in the bore 7.

The carrier 4 is of less diameter than the cavity 3 and is encircled by a ring 8 in which 85 it is freely slidable the ring having a sliding fit in the cavity.

A striker is provided for functioning the primer which has a hollow frusto conical portion 9 formed with an outwardly projecting annular flange 10 and terminating in its vertex in a cylindrical stem 11. A firing pin 12 projects forwardly from the stem into the hollow portion.

The striker is held in spaced relation to 95 the carrier 4 by suitable means such as a coiled spring 13. Normally the striker is retained in unarmed position by the ring 8 abutting against one face of the flange 10 and holding the other face of the flange 100

against the extending portion of a washer 14 which encircles the striker and rests upon an annular shoulder surrounding the mouth of the cavity 3 against which it is bound 5 by a screw cap 15 which is threaded into the grenade body and serves to protect and cover the firing mechanism.

The ring 8 is held in position to retain the striker unarmed by a safety pin 16 which 10 is positioned in the bore 7 of the carrier 4 and a bore 17 formed in the grenade body and communicating with the cavity 3.

The bore 17 is countersunk to provide a housing for the head of the pin 16 and 15 for a coiled spring 18 confined between the head of the pin 16 and the bottom of the counterbore and tending to force the pin out of the bores 7 and 19 to release the firing mechanism to armed position. The pin 20 is held against expansion of the spring 18 preferably through the instrumentality of a wire or pin 19 which is inserted through alining bores formed in the body of the 25 grenade and head of the pin 16, the end of which pin 19 may be bent to form a loop 20 which may be grasped for the purpose of withdrawing the pin 19.

In use, a grenade is held in one hand ready to be thrown. With the other hand 30 the loop 20 is grasped and the pin 19 withdrawn releasing the pin 16 to expulsion under the force of the expanding spring 18; this releases the ring 8, primer carrier 4 and the striker.

35 When the grenade strikes an objective the firing mechanism will function even though the grenade strikes on its side as

the striker will fulcrum on one portion of its flange 10 as indicated most clearly in Fig. 3.

I claim:

1. A firing mechanism, including a casing, a ring slidable within the casing, a primer carrier slidable in the ring, a shoulder within the casing, a striker formed with an annular flange normally resting against the shoulder and adapted to fulcrum thereon when the casing strikes on its side and means for normally holding the parts in unarmed position and isolating a primer from the main charge.

2. A firing mechanism, including a casing, a ring slidable within the casing, a primer carrier slidable within the ring, a striker normally held against movement by the ring and releasable means for normally holding the ring and primer carrier against movement and isolating a primer from the main charge.

3. A firing mechanism, including a casing, a primer carrier slidable within the casing, a striker within the casing and means for locking the carrier and striker in unarmed position, including means for isolating a primer from the main charge.

4. A firing mechanism, including a casing, a primer within the casing, a shoulder formed within the casing and a striker formed with an annular flange normally resting against the shoulder and adapted to fulcrum thereon when the casing strikes on its side to prime the primer.

HALSTEAD P. COUNCILMAN.
